[57] CLAIM

The ornamental design for a hacksaw, substantially as shown and described.

DESCRIPTION

FIG. 1 is a side elevational view of the hacksaw design of my invention, the opposite side being the mirror image thereof,

FIG. 2 is a top plan view of the design,

FIG. 3 is a bottom view,

FIG. 4 is an end view of my new design as taken from the left of FIG. 1, and

FIG. 5 is an end view of the design as taken from the right of FIG. 1.

FIG. 1.

FIG. 2.

FIG. 3.

FIG. 4.

FIG. 5.
